UNITED STATES PATENT OFFICE

155,840

DESIGN FOR A GAME BOARD

Robert L. Robbins, Jr., Hollywood, Calif., assignor,
by mesne assignments, to Milton Bradley Company,
a corporation of Massachusetts

Application March 2, 1948, Serial No. 144,870

Term of patent 14 years

(Cl. D34—5)

To all whom it may concern:

Be it known that I, Robert L. Robbins, Jr., a citizen of the United States, residing at Hollywood, in the county of Los Angeles and State of California, have invented a new, original, and ornamental Design for a Game Board, of which the following is a specification, reference being had to the accompanying drawings, forming part thereof.

Figure 1 is a top perspective view of the game board, showing my new design;

Figure 2 shows certain circles in Figure 1, which have been enlarged to make more clear the pictures appearing in these circles;

Figure 3 shows the circular area of the map of Figure 1, on a larger scale for clarity; and

Figure 4 is two portions of the game board of Figure 1, shown on a larger scale for purposes of clarity.

The game board is shaded to indicate color contrast.

I claim:

The ornamental design for a game board, as shown and described.

ROBERT L. ROBBINS, JR.
